UNITED STATES PATENT OFFICE.

WILLIAM B. LASSCELL, OF BAYONNE, NEW JERSEY, AND CHARLES H. WILLCOX, OF NEW YORK, ASSIGNEES TO THE WILLCOX & GIBBS SEWING MACHINE COMPANY, OF NEW YORK, N. Y.

STRAW-HAT-SEWING MACHINE.

SPECIFICATION forming part of Letters Patent No. 269,215, dated December 19, 1882.

Application filed March 1, 1882. (Model.)

To all whom it may concern:—

Be it known that we, WILLIAM B. LASSCELL and CHARLES H. WILLCOX, the former of Bayonne, Hudson county, New Jersey, and the latter of New York city, county and State of New York, have invented a new and useful Improvement in Straw-Hat Machines, which improvement is fully set forth in the following specification.

- 10 This invention has reference to a table adapted to be brought into position to form a continuation of the sewing-machine work-plate, or to be moved out of the way at the will of the operator. It is more particularly designed 15 for use in the machines for sewing straw braid into a hat in order to form a support in sewing to the tip or top of the crown of the hat, whence it is technically known as a "tip-table;" but it can be applied to other purposes. 20 The objections to the ordinary method of making tips (which this invention is designed to overcome) are, that in rapid-running machines great care has to be used in keeping the button or small circle of the tip up to the work- 25 guide, so that the needle will stitch through the tip and the entering braid or plait, and in doing this the operator unconsciously crowds the tip up against the work-guide with more force than is necessary, and by so doing, as 30 the tip grows in size, it is made to assume a dishing or concave condition, so that after the tip is turned down to sew the crown, and after the crown is made, the tip will be found to be concave or dishing and much lower at the 35 center than at the edge. This serious defect has to be overcome by what is known as the "setting-up" process, which includes stretching the tip over a block while wet with a solution of glue-water, and the hat is left to dry 40 on the block. After taking the hat off the block, if the tip is found not stiff enough to stand up, it is further supported by putting in a tip of paper on the under side of the hat-tip, with glue, and then set up again under heavy 45 pressure in a hydraulic press, all which operations are expensive in time and labor. Now, if the tip can be sewed flat from the button out to the edge of the crown, the tip will remain flat and render the setting-up process

unnecessary. This is accomplished by the 50 flat tip-table, which serves as a support to rest the tip upon, so that the operator cannot make the tip concave or dishing, and by the exercise of the slightest care will make every tip nearly as flat as the tip-table itself. The table 55 is preferably made tilting on a horizontal axis, and is upheld in position to form an extension of the work-plate by lugs having inclined faces and held in engagement by a spring, so that it can be removed by simple pressure of the 60 operator's fingers on the table.

The accompanying drawings, which form a part of this specification, illustrate what is deemed the best method of carrying the invention into effect.

Figure 1 is a front elevation of part of a straw-hat-sewing machine provided with a tip-table; Fig. 2, a view in plan and horizontal section, showing the construction of the tip-table and the manner of its attachment; and 70 Figs. 3 and 4 are partial views, in perspective, of the table detached.

The tip-table consists of a plate, A, fixed at the end of a supporting-arm, B, by means of a screw, a, and steady-pins a'. The arm B is 75 provided at its inner end with a hollow boss, b, which fits snugly within the counterbored recess b' in the machine-frame C, and receives the screw-stud D, which is tapped at its inner end into the machine-frame. On this stud D, 80 between the end of the boss b and the bottom of the counterbored recess b', is a washer, c, provided on its outer face with lugs c', and on the inner face grooved, as shown in Figs. 3 and 4, or otherwise roughened. When the 85 screw is in place the washer c is held firmly between the shoulder d on the screw-stud and the bottom of the recess b', and the roughened inner surface being pressed against said bottom the washer is effectually prevented 90 from turning. Screwed fast on the inner end of the boss b is a ring, e, notched, as shown at e', to receive the lugs c'. The notches e' could be made in the boss itself; but as this would ordinarily be made of cast-iron in one 95 piece with the arm B, it is preferred to use an additional steel ring.

A spring, E, is placed within the boss b, sur-

rounding the shank of stud D, and bears at one end against the under side of the head of the stud and at the other against the interior shoulder, f, on the boss b. This spring tends to force 5 boss b and the arm B inward, and, when the lugs c' are in the notches e', it holds them in engagement. The boss b is capable of a small endwise movement on the stud D and within the counterbored recess b' in the machine-frame. When 10 the arm B is turned the inclined faces of the lugs c' act upon the inclined sides of the notches e' and force the arm B and boss b outward against the pressure of the spring E. When 15 the arm B is turned a sufficient distance to release the lugs from the notches, it will drop down by the action of gravity or will remain in any position in which it may be placed, and when it is turned back the spring E forces the boss b with the notches c' into engagement 20 with the lugs c', which uphold the arm B and plate A until sufficient pressure is applied to compress the said spring and retract the boss. The pin g holds the washer c in place on the screw when the tip-table is separate from the 25 machine.

In attaching the table to the machine the lugs c' on the washer c are made to take their position in the notches e', and the boss b and screw-stud D are inserted in the counterbored 30 recess b'. The plate A is adjusted against the work-plate F of the sewing-machine flush with the top of said work-plate, and the stud D is screwed into the frame, securing the washer c in the position it then occupies. The roughness of the inner face of the washer prevents 35 it from moving, so that when turned up the plate A always comes to the proper position with respect to the work-plate. In the machine shown, as will be seen from the drawings, the work-plate is elevated by the frame 40 above the table or stand on which it is placed.

G is the presser-foot of the sewing-machine; H, the work-guide; I I', the guides for the entering braid. These parts may be of 45 any ordinary or suitable construction. As shown, they are constructed substantially as described in Letters Patent No. 218,413, granted to Charles H. Willcox August 12, 1879. In Fig. 1 the tip K and entering braid L are 50 shown in dotted lines.

In operation the tip can be held upon the plate A or tip-table, and, a slight resistance being applied by the fingers of the operator, the entering braid L is fed along fast enough 55 to enable the tip to be made perfectly flat. As soon as the tip has been formed, a touch of the hand throws the tip-table out of action, and the crown can then be turned down without interference from the tip-table.

60 The machine is ordinarily supported at the edge of a bench or table, Q, so that the work-plate projects beyond the bench. When the tip-table is moved out of action it drops down vertically, the arm B (shown in dotted lines, 65 Fig. 1) fitting into a groove, R, formed in the edge of the bench. The work-plate is thus left entirely free. The tip-table is also shown

in Fig. 1 in an intermediate position by dotted lines. In beginning a new tip the plate A is moved back into its original position, in which 70 it is held by the engagement of the lugs c' in the notches e' under the pressure of the spring E.

It is obvious that modifications can be made in the details of construction, and that parts 75 of the invention may be used separately.

Having now fully described our said invention, and the manner of carrying the same into effect, what we claim is—

1. The combination, with a sewing-machine, 80 of a table movable into position to form an extension of the work-plate and capable of being thrown out of action by pressure, as of the operator's hand applied to said table, substantially as described. 85

2. The combination, with a sewing-machine, of a tilting table formed of a plate, a supporting-arm attached to and depending from the bottom of said plate, and means for attaching the arm to the machine-frame below the work-plate of the machine, substantially as described. 90

3. The combination, with the supporting-arm, the hollow boss provided with notches, the screw, and spring, of the washer roughened on one face and provided on the other with lugs 95 adapted to engage said notches, substantially as described.

4. The combination, with a sewing-machine and the guides for sewing straw braid into a 100 hat, of a movable tip-table adapted when in action to form an extension of the work-plate, and to be put into and out of action, as required, so that the said machine is adapted to the continuous sewing of the crown of the 105 hat, substantially as described.

5. The combination, with a frame and an arm having a hollow boss fitting within a counterbored recess in said frame, of the stud, 110 spring, and lugs having inclined faces, substantially as described.

6. The combination, with the work-plate and frame of a sewing-machine, of a tilting table comprising a plate, supporting-arm with hollow boss having notches, screw-stud, washer 115 provided with lugs, and spring, substantially as described.

7. The combination, with a sewing-machine having a work-plate raised above the stand on which the machine is placed, of a table supported by an arm attached to the machine-frame, as explained, said table being adapted to be moved up to a level with the work-plate or to be moved down out of action by pressure applied to the table, substantially as described. 125

In testimony whereof we have signed this specification in the presence of two subscribing witnesses.
